ELECTRICAL CORD PLUG

Arthur Greenbaum, New York, N. Y., assignor to
Academy Electrical Products Corp., New York,
N. Y., a corporation of New York

Application May 3, 1949, Serial No. 2,405

Term of patent 14 years

(Cl. D26—1)

To all whom it may concern:

Be it known that I, Arthur Greenbaum, a citizen of the United States of America, and a resident of New York, in the county of the Bronx and State of New York, have invented a new, original, and ornamental Design for Electrical Cord Plug, of which the following is a specification, reference being had to the accompanying drawings, forming a part thereof.

Fig. 1 is a side elevational view of an electric cord plug showing my new design.

Fig. 2 is a top elevational view.

Fig. 3 is an inner end elevational view.

Fig. 4 is an outer end elevational view thereof.

The dominant features of my design reside in the body of the cord plug shown in full lines in the drawing.

What is claimed is:

The ornamental design for an electrical cord plug, substantially as shown and described.

ARTHUR GREENBAUM.
